his Atty.

UNITED STATES PATENT OFFICE

WALTER STOCK, OF LOS ANGELES, CALIFORNIA

RAZOR STROP

Application filed June 24, 1931. Serial No. 546,601.

This invention relates to devices used in resharpening razor-blades.

One of the objects of this invention is to provide a stropping device in which the side-
wise shifting of an inserted razor blade by means of the holder parts of the device and the rotating movements of the sharpening members of the device are jointly operative by the same operating means.

Another object is to provide a device in which one-edged as well as two-edged blades can be sharpened equally well.

Another object is to make the blade holder parts removable and exchangeable to facilitate an insertion of any type of blade.

Another object is to provide a device in which the turning as well as the shifting movements in one direction are produced manually while such movements in the opposite direction are produced automatically.

Other objects will appear from the following description and appended claim as well as from the accompanying drawing, in which—

Fig. 1 is a cross section through the blade-holders and sharpening members on line 1—1 of Fig. 2.

Fig. 2 is a longitudinal midsectional view of a simple strop approximately on line 2—2 of Fig. 1.

Fig. 3 is a cross section on line 3—3 of Fig. 2, illustrating the cooperative parts for tilting the blade-holders automatically by means of the swingably mounted outer drum.

Fig. 4 is a cross section on line 4—4 of Fig. 2, illustrating the parts by which the outer drum is oscillated by means of the flexible operating or pulling member as this member is being drawn from the casing or released to go back into the casing.

Fig. 5 is a fragmentary somewhat schematic illustration of a slightly modified form of sharpening members or rollers arranged to simultaneously contact the opposite edges of two-edged blades.

Fig. 6 is a somewhat diagrammatic illustration of circles to represent the interengagement of the gears of the slightly modified form of Fig. 5.

The casing 7 is provided with a boss 8 upon

which the spring 9 is mounted for controlling the movements of the inner drum 10, one end of the spring being secured to or engaged with the boss as indicated at 11 while the other end of the spring is secured to or engaged with the drum 10, by which the drum is held under tension in one direction turnable with respect to the casing.

To the outside of the inner drum 10, a flexible operating or pulling member 13 is secured or attached as indicated at 14, by which the inner drum can be rotated against the tension of the spring 9.

Gears 15 and 16 operatively connect the sharpening members 17 to the inner drum 10 so that the rotation of the inner drum results in a rotation of the sharpening members or rollers 17.

When a razor-blade 18 is inserted between the holding members 19 it can be swung either to the one or the other of the sharpening members 17 to bring the razor-edge into contact with the surfaces of these sharpening members while the sharpening members are being rotated and while the blade is shifted back and forth in a customary and desired manner for properly sharpening the razor-blade.

The turning or swing as well as shifting movements are made possible by means of the shaft-like portion 20 from which the holding members 19 project in a sidewise direction.

This shaft-like portion 20 is provided with a hook-like end 21 to engage with the screw-end 22, which is a rigid part of the structure embodying the inner drum 10 and the gear 15, so that, upon a rotating of the drum and gear and screw, the shaft-like portion 20 by means of the hook-end 21 is shifted endwise while sliding along the threads of the screw, such endwise sliding of the portion 20 being within the sleeve-portion 23 of a tilting control-member.

A slot or cut-out 24 in the sleeve-portion 23 facilitates the insertion of the blade-holder from the end of the sleeve and also the sliding of the shaft-like portion of the blade-holder within the sleeve while the edges along the slot abut firmly against the sides of the blade-holders, the sleeve being turnable with-

in the bearings 25 and 26, the turning of the sleeve being controlled by the lever 27.

Inasmuch as the edges along the slot 24 abut closely against the sides of the holder members 19, as clearly illustrated in Fig. 1, and the movements being controllable by the lever 27 on the sleeve 23, any swinging movement of the lever 27 and therewith any oscillating movement of the sleeve 23 results in a corresponding oscillating movement of the blade-holder.

To produce such oscillating and combined endwise movement for the blade-holder by means of the screw-end 22 and the lever 27, these two parts are jointly operated by a common mechanism, the operating parts for the screw-end 22 having been described above, to result in the endwise shifting of the blade-holder by means of the engagement 21—22, while the lever 27, by means of the pin 28, is operatively engaged with the outer drum 29, which is turnably or rather oscillatory mounted with respect to the inner drum 10, and operative by means of the flexible pulling or operating member 13.

The outer drum 29 is normally held with its shoulder-piece 30 abutting against the shoulder-piece 31 of the casing 7, under the tension of the spring 32, the casing 7 having been provided with a slot 33 with guiding-edges 33_a, and the outer drum having an aperture 34 with guide-edges 34_a, so that the pulling member 13 is brought to the bent position indicated at 13_a in inoperative position.

Upon a drawing of the flexible member 13 from the casing 7 through the slot 33, on having to overcome the tension of the spring 9, the flexible member 13 straightens out sufficiently to press against the guiding-edge 34_a of the slot in the outer drum 29, to rotate or swing this drum against the tension of the spring 32 until the guide-edge 34_a reaches the position indicated at 34_b in Fig. 4, the straightening of the flexible member being indicated in dotted lines at 13_b, thereby imparting a swinging movement to the lever 27 by means of the pin 28 on the outer drum 29.

A further drawing of the flexible member results in a turning of the screw-end 22 and thereby in a shifting of the blade-holder as well as in a rotating of the sharpening members 17 by means of the gears 15—16.

As the flexible member is released, all movements are reversed, the spring 9 serving to rotate the screw-end 22 and the gears 15—16 in the opposite directions, and the spring 32 returning the outer drum to its normal inoperative position and thereby swinging the blade-holder in the opposite direction.

From the above it will be understood that by a combination manual and automatic operation the two opposite sides of a single cutting edge are sharpened, or, in other words, a sharpening of a single-edged razor-blade

can be accomplished by an alternating pulling and releasing of the flexible member 13.

Furthermore, it must be understood that the two opposite edges of a two-edged razor-blade can be placed into sharpening positions within this device one after the other.

On the other hand, it must be understood that the device can easily be modified to accommodate both edges of a two-edged razor-blade.

Such a slight modification is easily explained on the rough outlines of the gears in Figs. 5 and 6. Assuming the gear 15 to be the same as in Fig. 2 with the same or a similar function and also the same or similar operative connections, this gear 15 of Fig. 5 to be represented by the circle 15_a in Fig. 6, wider intermediate pinions 36 of Fig. 5, represented by the circles 36_a in Fig. 6, can readily be meshed with other gears 37 in Fig. 5 as represented by the circles 37_a in Fig. 6, whereby a simultaneous sharpening of the opposite edges of a two-edged razor-blade can easily be accomplished while the blade swings to either the position indicated at I_a or II_a, by eventually a similar shaft-like member as indicated at 20 in Fig. 2, which certainly will easily be understood without further illustration.

Having thus described my invention, I claim:

In a razor-strop, sharpening-members, a blade-holder, a rotating mechanism including a screw-end, an engagement between the said screw and said blade-holder whereby the blade-holder can be moved endwise, means for operatively connecting the rotating mechanism with the sharpening-members, a tension-means for operating the rotating mechanism in one direction, a flexible member for manually operating the rotating mechanism in the opposite direction against the tension of the tension-means, a drum concentrically mounted to rotate around said tension-means and having an aperture through which the said flexible member passes outwardly, an engagement between the drum and blade-holder adapted to swing the blade-holder to opposite positions with respect to said sharpening-members, and a spring for actuating the drum to swing to one position when the flexible member is released while yielding to a pulling and thereby a straightening of the flexible member adapted to result in a contacting of the flexible member with a wall of said aperture and thereby resulting in a swinging of said drum and therewith of said blade-holder to the opposite position.

In testimony that I claim the foregoing as my invention I have signed my name.

WALTER STOCK.
